UNITED STATES PATENT OFFICE.

WILBUR A. GOODWIN, OF RAINIER, WASHINGTON.

GATE AND DOOR CONTROL.

Application filed May 2, 1924. Serial No. 710,592.

To all whom it may concern:

Be it known that I, WILBUR A. GOODWIN, a citizen of the United States, residing at Rainier, in the county of Thurston and State of Washington, have invented a new and useful Gate and Door Control, of which the following is a specification.

This invention aims to provide novel and simple means whereby a door, gate or other barrier may be opened and closed by a moving vehicle, it being unnecessary for the driver of the vehicle to alight.

It is within the province of the disclosure to improve generally and to enhance the utility of devices of that sort to which the invention appertains.

Although a preferred form has been shown, it will be understood that a mechanic working within the scope of what is claimed, may make such changes as his skill may dictate, without departing from the spirit of the invention.

In the drawings:—Figure 1 shows in elevation, a device constructed in accordance with the invention, parts appearing in section; Figure 2 is a top plan wherein parts are sectioned away; Figure 3 is an elevation in which the device is viewed at right angles to the showing of Figure 1; Figure 4 is a sectional detail showing the relation existing between certain of the levers and latches; Figure 5 is a sectional view showing the cooperation between one of the levers and attendant parts; Figure 6 is a fragmental sectional view wherein one of the latches is shown in holding relation to the barrier; Figure 7 is a top plan showing a slight modification in the means for connecting the operating shaft with the barrier.

The device forming the subject of this application may be used for operating one or more doors for a garage, or one or more gates in the open, but by way of illustration, the drawings show a support 1 comprising a hollow platform 20 and an upstanding frame 2, barriers 3 being mounted at 4 on the frame 2, to swing horizontally. Top bars 5 are secured to the barriers 3 and carry beveled gear wheels 6 located concentrically with the pivotal mountings of the barriers 3. The gear wheels 6 mesh with beveled pinions 7 secured to a horizontal shaft 8, located above the barriers 3, and journaled in the frame 2.

Flexible members 9 and 10 are provided, the flexible member 10 including a cable or

the like, indicated at 11, and a retractile spring 12 connected to the cable, the flexible member 9 comprising a cable 14 and a retractile spring 15. The flexible elements 11 and 14 are wound in opposite directions about the ends of the shaft 8, the lower end of the spring 15 being connected to the outer end of a supplemental lever 16. A latch 17 is disposed parallel to the lever 16, the lever and the latch being fulcrumed intermediate their ends on the lower portion of the frame 2. At its outer end, the latch 17 has a beveled keeper 19, adapted to hold one of the barriers 3 in an open position, and, in fact, to hold both barriers open, since the barriers are connected by the gear wheels 6 and the pinions 7 with the shaft 8.

A main lever 22 is disposed at right angles to the lever 16 and the latch 17 and is fulcrumed at 23, intermediate its ends, on the platform 20. A retractile spring 21 is connected at its ends with the frame 2 and with the latch 17, and tends to swing the inner end of the latch 17 downwardly on the inner end of the main lever 22 and to elevate the outer end of the latch 17 and the keeper 19 into the position shown in Figure 1, so that, when the barriers 3 are opened, as hereinafter explained, one barrier will engage automatically with the keeper. An auxiliary lever 24 is disposed in alignment with the main lever 22 and is located on the opposite sides of the barriers 3 from the main lever 22, the lever 24 being fulcrumed at 25, intermediate its ends, on the platform 20. The inner end of the auxiliary lever 24 extends beneath the inner end of the main lever 22, as shown in Figures 4 and 3. At its outer end, the lever 22 carries a tread plate 26 adapted to be engaged by a vehicle wheel, and the lever 24 is provided at its outer end with a similar tread plate 27.

A main lever 28 is disposed parallel to the main lever 22 and is located on the same side of the barriers 3 as the lever 22, the lever 28 being fulcrumed intermediate its end at 29 on the platform 20. At its outer end, the lever 28 is supplied with a tread plate 30. A latch 31 is located within the hollow platform 20 and is fulcrumed intermediate its ends, as at 32, on the platform. At its inner end, the latch 31 has a beveled keeper 33 operating in an opening 34 in the platform 20 and adapted to engage both barriers 3,

to hold them closed. A retractile spring 35 is connected to the interior portion of the platform 20 and to the latch 31 and tends to draw down the outer end of the latch 31 and on the inner end of the main lever 28. The spring 12 of the flexible member 10 is connected to the outer end of a supplemental lever 36, the inner end of the lever 36 resting on the main lever 28, as shown in Figure 5, the lever 36 being fulcrumed intermediate its ends, as at 37, on the lower portion of the frame 2. An auxiliary lever 38 is disposed on the opposite side of the barriers 3 from the lever 28, the inner end of the lever 38 being engaged beneath the inner end of the lever 28, the lever 38 being fulcrumed intermediate its ends, as at 39, on the platform 20, and being provided at its outer end with a tread plate 40.

Suppose that the barriers 3 are closed as in Figure 1 and that a vehicle approaches in the direction of the arrow A in Figure 2. The vehicle is run over the tread plate 30 and the lever 28 is tilted, the latch 31 being tilted and the keeper 33 being disengaged from the barriers 3. At the same time, the lever 36 is tilted, the spring 12 is extended, and the cable 11 is unwound from the shaft 8, the shaft 8 being rotated, and the pinions 7 and the gear wheels 6 opening the barriers 3 until one barrier engages behind the keeper 19 on the latch 17, to hold the barriers open. After the vehicle has passed the open barriers 3, the vehicle is run over the tread plate 27, the lever 24 being tilted, the lever 24 tilting the lever 22, and the lever 22 tilting the lever 16 and the latch 17, the keeper 19 being disengaged from the open barrier, and both barriers being swung to closed position, when the lever 16 is tilted, because the spring 15 is expanded and the cable 14 unwound from the shaft 8, reverse rotation being imparted to the shaft, and the pinions 7 cooperating with the gear wheels 6 to close the barriers 3, the barriers engaging again with the keeper 33 on the latch 31.

When the vehicle is moving in the direction of the arrow B in Figure 2, the vehicle is run over the tread plate 40, the lever 38 being operated, and the lever 38 operating the lever 28 to disengage the keeper 33 from the barriers and to open the barriers through the instrumentality of the lever 36 and the flexible member 10, as hereinbefore explained. The vehicle finally is run over the tread plate 26, the keeper 19 is disengaged from the open barrier, and the lever 16, together with the flexible member 9, operate to close the barriers.

When the device is used to operate a garage door, rather than a gate, the levers 38 and 24 may be omitted. Under such circumstances, the barriers 3 are opened by means of the lever 28 when the vehicle enters the garage, and are closed by an oper-

ator. Likewise, when the vehicle leaves the garage, the barriers are opened by an operator and are closed when the vehicle is run over the tread plate 26 on the lever 22.

Although two barriers 3 are shown, it will be obvious, without specific illustration, that the device will operate one barrier quite as well as it will operate two.

Passing to the modification shown in Figure 7, it will be obvious that the beveled gears 6 and 7 of Figure 1 need not be used to connect the shaft 8 with the barriers 3. Thus in Figure 7, the barrier 41 may be provided with a worm wheel 42 engaged with a worm 43 on a shaft 44, corresponding to the shaft 8, the flexible operating member for the shaft 44 being marked by the numeral 45.

I claim:

1. In a device of the class described, a support, a barrier mounted to swing on the support, a shaft journaled on the support, means for connecting the shaft operatively with the barrier, main levers fulcrumed intermediate their ends and located on the same side of the barrier, the outer ends of the main levers being so located as to be engaged by a vehicle, supplemental levers fulcrumed intermediate their ends and disposed transversely of the main levers, the inner ends of the supplemental levers being engaged with the inner ends of the main levers, flexible members wound in opposite directions about the shaft and connected to the outer ends of the supplemental levers, latches fulcrumed intermediate their ends and disposed approximately parallel to the supplemental levers, the inner end of one latch cooperating with the barrier to hold the barrier closed, and the outer end of said latch being engaged with the inner end of one main lever, and the outer end of the other latch cooperating with the barrier to hold the same open, the inner end of the last specified latch being engaged with the inner end of the other main lever.

2. A device of the class described, constructed as set forth in claim 1, and further characterized by the provision of auxiliary levers disposed on the opposite side of the barrier from the main levers and having their outer ends so located as to be engaged by a vehicle, the inner ends of the auxiliary levers being engaged with the inner ends of the main levers, and the auxiliary levers being fulcrumed intermediate their ends.

3. In a device of the class described, a support, a barrier mounted to swing on the support, a shaft journaled on the support, means for connecting the shaft operatively with the barrier, a main lever fulcrumed intermediate its ends, the outer end of the main lever being so located as to be engaged by a vehicle, a supplemental lever fulcrumed intermediate its ends and disposed trans-

versely of the main lever, the inner end of the supplemental lever being engaged with the inner end of the main lever, a flexible member wound about the shaft and connected to the outer end of the supplemental lever, a latch disposed parallel to the supplemental lever and fulcrumed intermediate its ends, the inner end of the supplemental lever cooperating with the inner end of the main lever, and the outer end of the latch coacting with the barrier to hold the barrier open.

4. In a device of the class described, a support, a barrier mounted to swing on the support, a shaft journaled on the support, means for connecting the shaft operatively with the barrier, a main lever fulcrumed intermediate its ends, the outer end of the main lever being so located as to be engaged

by a vehicle, a supplemental lever fulcrumed intermediate its ends and disposed transversely of the main lever, a latch fulcrumed intermediate its ends, the inner end of the supplemental lever and the outer end of the latch coacting with the main lever, the inner end of the latch cooperating with the barrier to hold the barrier closed, and a flexible member wound about the shaft and connected to the outer end of the supplemental lever.

In testimony that I claim the foregoing as my own, I have hereto affixed my signature in the presence of two witnesses.

WILBUR A. GOODWIN.
